BELT OR SIMILAR ARTICLE

Angie E. Carpenter, Boston, Mass.

Application October 8, 1953, Serial No. 27,109

Term of patent 7 years

(Cl. D3—10)

To all whom it may concern:

Be it known that I, Angie E. Carpenter, a citizen of the United States, residing at Boston, in the county of Suffolk and Commonwealth of Massachusetts, have invented a new, original, and ornamental Design for a Belt or Similar Article, of which the following is a specification, reference being had to the accompanying drawing forming a part thereof in which:

Fig. 1 is a plan view of a belt or similar article showing my new design, and

Fig. 2 is a view in perspective of the belt or similar article in its assembled form showing my new design.

I claim:

The ornamental design for a belt or similar article, substantially as shown.
